UNITED STATES PATENT OFFICE.

CHARLES CONNOLLY, OF TURNER'S FALLS, MASSACHUSETTS.

FIRE-ESCAPE.

SPECIFICATION forming part of Letters Patent No. 288,411, dated November 13, 1883.

Application filed June 12, 1883. (No model.)

To all whom it may concern:

Be it known that I, CHARLES CONNOLLY, a citizen of the United States, residing at Turner's Falls, in the county of Franklin and State of Massachusetts, have invented new and useful Improvements in Fire-Escapes, of which the following is a specification.

This invention relates to improvements in portable fire-escapes, the object being to provide improved operating devices for fire-escapes of this class, whereby they are brought under more perfect control of the operator and greater safety is secured.

In the drawings forming part of this specification, Figure 1 illustrates a portion of a front of a building having suspended therefrom a fire-escape constructed according to my invention. Fig. 2 is an edge view of the frame, showing certain parts removed. Figs. 3 and 4 are detail views.

In the drawings, D represents a portion of the wall of a building, having secured by the side of the window thereof a bracket, A, to which a rope, b, is attached, which reaches to the ground. The rope b may be attached to the building in any other secure manner, so that it descend within convenient distance of the windows or other openings in the wall.

The fire-escape apparatus, embodying the mechanism whereby a person is able to descend from a building to the ground from a window therein or other point, and control his motion in conjunction with said rope b, consists of a rectangular frame, made by uniting two side rails, d d, having longitudinal grooves therein of T shape in cross-section, by cross-bars o o at each end, and having hung between said rails elastic-faced rollers v x and a roller, v', and provided with means for moving rollers x, and with a suitable seat for a person, as hereinafter set forth.

The rollers above named, excepting roller v', are made with elastic surfaces by covering them with rubber or other suitable frictional substance. Those lettered v are hung in suitable bearings centrally located between the sides of the frame, which bearings are rigid upon the latter. The rollers x, located below the said rollers v, are supported in movable boxes or bearings e, which are fitted into the aforesaid T-shaped grooves in the

rails d, their shafts passing through slots in said rails, as shown in Fig. 1. The said rollers v are supported in bearings of the same diameter as the rollers, and the elastic frictional surface of said rollers is brought directly in contact with the interior surface of said bearings for the purpose of creating a certain amount of frictional resistance, to retard the rotation of the rollers v, when the rollers x, 60 having the rope b between them, and the rollers v are forced against them, as hereinafter set forth.

The boxes e of each side of the frame are connected together by a rod, i, and a screw-rod, a, provided with a suitable hand-wheel on its lower end, is connected with each of the lower boxes, e, by a swivel connection, as shown in dotted lines in Fig. 4, whereby the boxes e and the rollers x, which are supported therein, can, by a person seated in the apparatus and operating the screw-rods a, be moved toward and from the rollers v.

A roller, v', is hung on the frame, to one side and out of the line of the rollers x and v, around which the rope b passes, to cause it to take an angular course as it passes over the roller above and below it and give the rope more of a surface-bearing on said rollers than it would otherwise have.

Two brackets, y y, are secured to the frame, one on either side, to which are attached two ropes, n, supporting a seat, w. A strap, m, is attached to the ropes n, which is adapted to be buckled around the body of a person seated in the apparatus, as shown in Fig. 1.

The operation of my apparatus is as follows: The apparatus is supplied with the rope b, which is connected therewith, passing from end to end between the rollers thereof, as shown, 90 and when to be used the upper end of the rope is made fast to the bracket A, or other suitable object. The screws a are turned to force the rollers x x firmly against the rollers v, clamping the rope b therebetween, so that 95 the fire-escape cannot move on the rope when the weight of a person is added to it. The person wishing to descend now seats himself on the seat w, buckling strap m around him, and grasping the hand-wheels of the screw-rods a, as shown in Fig. 1, he turns the latter sufficiently to reduce the pressure of roll-

ers x against rollers v , thereby permitting the apparatus and the person to descend slowly and safely on rope b to the ground.

This device is adapted to be made of such dimensions as to be portable, and be carried in a trunk; or each room of a hotel or other building may be supplied with one, and with suitable means for keeping the rope b permanently attached to the building, so that it will always be ready for use.

What I claim as my invention is—

A fire-escape consisting of a rectangular frame having side rails, d d , each provided

with a longitudinal groove therein, boxes e , fitted to slide in said grooves, and united in 15 pairs by the rods i , the elastic-faced rollers xx , having bearings in said boxes, the screw-rods a a , the elastic-faced rollers v v , hung in fixed bearings in said rails, the roller v' , hung to one side of said frame, a seat, w , suspended to 20 the latter, and the rope b , combined and operating substantially as set forth.

CHARLES CONNOLY.
